UNITED STATES PATENT OFFICE.

DAVID C. BOYD, OF GALION, OHIO, ASSIGNOR TO THE GALION IRON WORKS AND MANUFACTURING COMPANY, OF GALION, OHIO, A CORPORATION OF OHIO.

PINION DEVICE OPERATING MECHANISM.

1,147,366.

Specification of Letters Patent.

Patented July 20, 1915.

Application filed October 3, 1913. Serial No. 793,147.

To all whom it may concern:

Be it known that I, DAVID C. BOYD, a citizen of the United States, residing at Galion, in the county of Crawford and State of Ohio, have invented certain new and useful Improvements in Pinion Device Operating Mechanism, of which the following is a specification.

This invention relates to new and useful improvements in road machines of that type which embody a wheel-supported frame-work, vertically adjustable and rearwardly diverging draw bars suspended by the frame-work, a revolubly adjustable blade support or "circle," as it is called, carried by the draw bars and a reversible scraping blade carried by said circle and means carried by the frame-work and connected to the respective draw bars at the rear ends 20 of the latter, whereby said ends may be elevated or lowered to the required point, one independently of the other, as required by the work in hand.

To those versed in the art to which this invention appertains, it is well known that it has been heretofore customary to raise and lower the rear ends of the draw bars by means of vertically disposed rack bars held for a vertically sliding movement in 30 guiding and supporting brackets, said rack bars having link rod connections with the rear ends of the draw bars and being raised or lowered by means of spur pinions meshing with the teeth of the rack bars, said pinions being secured to the ends of shafts journaled in said guiding supports or brackets and being provided at their inner ends with relatively large hand wheels designed to be grasped by the attendant or operator on the 40 platform of the machine to turn said shafts in the required direction to raise or lower the racks, said hand wheels being usually engaged by spring-actuated brake blocks or shoes supported on the frame-work plat- 45 form and provided with treadles, whereby they may be released by the feet of the operator to permit the hand wheels to be turned. While this specific arrangement of parts for raising and lowering the rear ends 50 of the draw bars has its distinct advantages in that through the instrumentality of the meshing racks and spur pinions, a direct upward pull or lift is imparted to the weight carried thereby, yet there are inci- 55 dential and decided disadvantages, owing

to the fact that these brakes, just mentioned, are rendered necessary, as the same are not only unreliable and have a tendency to easily get out of order and thereby permit the rear ends of the draw bars to drop, but they manifestly require especial attention on the part of the operator and are thus found inconvenient and unsatisfactory. With a knowledge of these conditions, my invention aims primarily to improve this part or 60 feature of reversible road machines, whereby not only am I able to do away entirely with the use of brakes, but at the same time, combine with the advantageous features of a direct upward pull attained by a rack bar and spur pinion connection, the added important and advantageous feature of worm and worm gear operative connections combined with the rack and spur pinion gears, so that while I secure the characteristics in- 65 70 75 80 85 90 95 100 105 110

incidental to worm and worm gear connections which will hold the vertically movable rack bars at any elevation at which they are set and thus do away with brakes and at the same time secure the direct upward pull above mentioned, I reduce lost motion to a minimum, which lost motion can only be reduced in machines as at present constructed by the employment of excessively large worms. And the invention also aims 85 to generally improve machines of this class, so far as this feature thereof is concerned, so as to render them more useful and commercially desirable.

With these and other objects in view, as 90 will more fully appear as the description proceeds, the invention consists in certain constructions, arrangements and combinations of the parts that I shall hereinafter fully describe and claim.

For a full understanding of the invention, reference is to be had to the following description and accompanying drawing, in which—

Figure 1 is a side elevation of a portion 100 of a road machine, embodying the improvements of my invention, only so much thereof being shown as to render clear the construction and arrangement of parts in connection with the following description, some parts being omitted and other parts broken away. Fig. 2 is a view at right angles to Fig. 1, with parts in section, and Fig. 3 is a view in the nature of a diagram which will be entirely clear to those familiar with 105 110

this type of machine, and which is intended merely to illustrate the approximate position of my invention in relation to the other parts of the machine.

- 5 Corresponding and like parts are referred to in the following description and designated in the different views of the accompanying drawing by like reference characters.
- 10 Referring to the drawing, the numeral 1 designates one of the side sills of the wheel-supported frame-work of a road machine of the character hereinbefore generally described, and 2 designates brackets which 15 are secured to the side sills 1 by any desired means in the relative position illustrated in Fig. 3. The brackets 2 extend in the usual manner above and below the side sills 1 of the frame-work, it being understood 20 that there are two of these disposed in transverse relation to each other on opposite sides of the frame-work, but as they are both alike, a description of one will suffice. The vertically disposed bracket 2 25 is formed with upper and lower guide flanges 3 which serve to engage and support a vertically disposed rack bar 4 for a vertically sliding movement therein, said rack bar being formed with the usual 30 strengthening web or rib 5 and having rack teeth 6, as clearly illustrated in Fig. 2 and indicated in dotted lines in Fig. 1. These teeth face laterally of the machine, as will be clearly understood by reference to the 35 drawing, and mesh with a relatively large spur gear wheel 7 secured to a shaft 8 and mounted in a housing 9 which preferably forms an integral part of the bracket 2. A worm gear 10 is also secured to the transversely extending shaft 8 in addition to 40 the spur gear or pinion 7 which meshes with the rack teeth 6, and said worm gear is in meshing engagement with a worm 11 fixed upon a shaft 12 which extends at right angles to the shaft 8. On the inner end of 45 the shaft 12, a hand wheel 13 is secured. An eye 14 is cast on or secured in any desired way to the rack bar 4, preferably about midway of its length and disposed 50 in a plane parallel to the transverse plane of the rack teeth 6, said eye being designed for connection to the upper end of the link rod 15 which is, in turn, connected by a stirrup or other equivalent device at its 55 lower end to the rear end of one of the draw bars 16 (see Fig. 3).

From the foregoing description taken in connection with the accompanying drawing, the operation of my improved means for raising and lowering the rear end of a draw bar will be apparent. In the practical use of the device, it is only necessary for the attendant to turn the hand wheel 13 in the required direction, whereupon the meshing engagement of the worm 11 and worm 60 gear 10 and the motion transmitted through the shaft 8 to the meshing pinion 7 and rack teeth 6, will raise or lower the rack bar, as desired, and without any appreciable lost motion whatever, a direct upward pull 70 being imparted to the draw bar 16 and the rack bar remaining firmly at any elevation to which it is put, without the necessity of using brakes of any character whatever.

While the accompanying drawing illustrates what I believe to be the preferred embodiment of my invention, it is to be understood that the invention is not limited thereto, but that various changes may be made in the construction, arrangements and proportions of the parts without departing 80 from the scope of the invention, as defined in the appended claim.

What I claim is:—

In a machine of the character described, 85 the combination with a horizontally extending supporting member, of a bracket attached to the supporting member extending upward therefrom and having guides formed thereon and laterally displaced from the 90 body of the bracket, a vertically disposed rack slidingly supported in said guides, a link pivotally connected to the rack, a housing mounted upon the bracket, a shaft mounted upon the bracket disposed within 95 said housing and extending parallel to the supporting member, a pinion mounted upon the shaft and partially inclosed within the housing and having its teeth engaging the teeth of the rack, a worm gear wheel also 100 mounted upon the shaft and inclosed within the housing, a worm shaft mounted in the upper portion of the housing, a worm thereon engaging the worm gear wheel, and an operating device exterior to the housing 105 and attached to said worm shaft.

In testimony whereof I affix my signature in presence of two witnesses.

DAVID C. BOYD.
